(57) CLAIM

The ornamental design for a cosmetic package, as shown and described.

DESCRIPTION

FIG. 1 is a perspective front view of a cosmetic package, embodying the new design;

FIG. 2 is a front elevation view of the design shown in FIG. 1; and

FIG. 3 is a back elevation view of the design shown in FIG. 1.

FIG. 4 is a right side elevation view of the design shown in FIG. 1;

FIG. 5 is a left side elevation view of the design shown in FIG. 1;

FIG. 6 is a top view of the design shown in FIG. 1; and,

FIG. 7 is a bottom view of the design shown in FIG. 1.

The broken lines in the drawings are for illustrative purposes only and form no part of the claimed design.
